UNITED STATES PATENT OFFICE.

CARL DIENSTBACH, OF NEW YORK, N. Y., ASSIGNOR OF ONE-THIRD TO WALTER L. FAIRCHILD, OF NEW YORK, N. Y., AND ONE-THIRD TO WALTER L. FAIRCHILD, TRUSTEE, OF NEW YORK, N. Y.

FLYING-MACHINE.

1,104,639.

Specification of Letters Patent. Patented July 21, 1914.

Application filed April 12, 1910. Serial No. 555,240.

To all whom it may concern:

Be it known that I, CARL DIENSTBACH, of Brooklyn, New York, in the county of Kings, and in the State of New York, have 5 invented a certain new and useful Improvement in Flying-Machines, and do hereby declare that the following is a full, clear, and exact description thereof.

The object of my invention is to provide 10 a mechanism for controlling the lateral and longitudinal equilibrium of flying machines with greater efficiency and facility than has hitherto been possible.

In general, my invention contemplates the 15 application to an aeroplane of one or more horizontal propellers having blades so arranged that their angle of inclination can be changed at will by the aviator; the propeller or propellers being so arranged that 20 they are constantly rotated so that by changing the angle of the propeller blades at any time a positive or negative lift can be given to the part of the aeroplane at which the propeller is located.

By the use of this construction the equilibrium 25 of the aeroplane can be readily changed at all times, while at the same time the mechanism used for changing the equilibrium is practically free from the influence 30 of air currents or gusts of wind owing to the small area of the blades of the propeller.

A further advantage of my apparatus 35 flows from the fact that the mechanism used for changing the equilibrium of the device is equally effective in fast and slow flight. This is an especially advantageous feature, inasmuch as with the present types of aeroplanes, it is necessary to operate the aeroplane at a high speed in order to obtain an effective 40 use of the mechanism used for changing the equilibrium of the aeroplane. Especially is this true of the lateral equilibrium of the aeroplane. In fact, many of the disasters which have occurred in aviation have been 45 due to the inability of the operator to properly and readily control the lateral equilibrium of the aeroplane while the aeroplane is flying at a slow speed, as, for example, when it is either starting or stopping.

Still a further advantage of my apparatus 50 flows from the fact that the area of the prop-

eller blades is small and the propeller is, therefore, free from the influence of air currents or gusts of wind. This permits the propeller mechanism to be located at the end 55 of a long lever arm, thereby making it possible to obtain a more effective and a more rapid change of the equilibrium of the flying machine. It will be noted, also, that the effect of the propeller upon the equilibrium 60 of the aeroplane is capable of a perfect graduation from zero to a given maximum. I have shown certain embodiments of my invention in the accompanying drawings, in which—

Figure 1 is a rear elevation of an aeroplane equipped with my invention. Fig. 2 is a horizontal section of the same. Fig. 3 is a side elevation of the same. Fig. 4 is an enlarged detail of the form of my invention 70 shown in Figs. 1, 2 and 3. Fig. 5 is a plan view of the same. Fig. 6 is an elevation, partly in section, of the gear mechanism for operating the propeller blades. Fig. 7 is an elevation, partly in section, of another modification of rotating mechanism for the propeller, and Fig. 8 is a plan view of the same.

In the modification shown in Figs. 1 to 6, 1 represents a pair of supporting planes for an aeroplane, the planes 1 being provided with the usual stays 2. The planes 1 are supported upon three wheels 3 in the usual manner when the flying machine is upon the ground. The flying machine is provided with the usual front rudder guide 80 mechanism 3¹, the details of which are not shown, as they constitute no portion of my invention, and a rear rudder guide mechanism 3¹¹, the details of which are not shown for the same reason. A motor 4 is 85 carried upon the lower plane 1, which motor has a shaft 3 connected at one end to a vertical propeller 4¹ for driving the aeroplane and at the other end to a sheave 5. A cable 6 leads from the sheave 5 to a similar 90 sheave 7 for driving a horizontal propeller 8, the cable 6 being guided by means of grooved rollers 9 located upon the stays 2 of the aeroplane. The sheave 7 is carried in a bracket 10 which extends outwardly 95 from the outermost stays at one side of the aeroplane. The bracket 10 has an upper 100

arm 11 and a lower arm 12 for carrying the propeller 8, the upper arm 11 being bifurcated to form two arms 13 and 14. The sheave 7 is tightly secured upon a sleeve 15, designed to rotate in bearings in the ends of the arms 12, 13 and 14, the sheave 7 being located between the arms 13 and 14. The sleeve 15 is enlarged between the arms 12 and 14 to receive the inner ends of a plurality of propeller blades 16 each of said blades 16 carrying a gear 17 upon its inner end within the enlarged portion of the sleeve 15. The gears 17 mesh with a single gear 18 carried upon a sleeve 31 situated within a sleeve 19 which is secured by means of screws 19¹ to the sleeve 15. Above the sleeve 19 there is situated a hollow sleeve 19¹¹ which is fixedly secured to the end of the sleeve 31. Within the sleeve 19¹¹ there is situated a plunger 20 which has a rod 21 projecting laterally therefrom through a curved slot 22 located in the sleeve 19¹¹ into a vertical slot 23 located in the sleeve 15. A rod 24 passes through the center of the plunger 20 and carries beneath the plunger 20 a head 25 to prevent it from being withdrawn from the plunger. At the top of the rod 24 there is a right angle extension 25¹ which moves in the slot 26 carried in an arm 27 extending upwardly from the arm 13. The purpose of the slot 26 is to limit the movement of the right angle extension 25. The rod 24 is also provided at its upper end with an eye 28 to which is attached a cable 29 passing over a pulley 30 carried upon the extreme upper end of the arm 27. A cable 32 extends from the head 25 through the sleeve 31 outwardly over a pulley 33 which is carried upon a bracket 34 projecting from the arm 12. The cables 29 and 30 lead respectively over pulleys 35 and 36 to the upper and lower ends respectively of a manually operable lever 37 pivotally supported upon a bracket 38 affixed to the lower plane 1.

In the modification shown in Figs. 7 and 8, the construction is the same except that a sheave 39 is provided upon the outer periphery of the propeller, the sheave 39 being connected to the enlarged portion of the sleeve 15 by means of a plurality of wire spokes 40.

In the operation of the form of my invention shown in Figs. 1 to 6, the aeroplane is started from the ground in the usual manner by the operation of the propeller the aeroplane being allowed to run upon the wheels 3 until it leaves the ground. Once that the aeroplane has left the ground, the front and rear rudders 3¹ and 3¹¹ may be used to change the elevation of the aeroplane in the air. The lateral equilibrium of the aeroplane is maintained at all times by the operation of the lever 37 which changes the angle of the propeller blades 16. It will be

noted that owing to the fact that each propeller blade 16 has a greater portion of its area located at one side of the axis of rotation thereof than at the other side, that the propeller blades will normally assume a horizontal position, and, furthermore, that it requires a constant force exerted in opposition to the air pressure to change the angle of the propeller blades. This arrangement, therefore, permits the aviator to know at any time the angle of the propeller blades from the pressure exerted on the lever 37. The angle of the propeller blades can be changed in such a manner as to cause the side of the aeroplane to which the propeller is attached to be elevated or depressed at will at a very rapid rate.

The modification shown in Figs. 7 and 8 operates in the same manner, the cable 6 for rotating the propeller being extended in this case around the periphery of the propeller instead of above the same.

It will be noted that in either modification, the sheaves 7 and 39 act to some extent as fly-wheels. It will be noted also, that my invention is not necessarily confined to changing the lateral equilibrium of the aeroplane, but may be applied in such a manner also as to change the longitudinal equilibrium or the longitudinal equilibrium and lateral equilibrium simultaneously.

While I have described my invention above in detail, I wish it to be understood that many changes may be made therein without departing from the spirit of my invention.

I claim:

1. In a device of the character described, an aeroplane, a propeller for changing the equilibrium thereof, and means for changing the angle of the propeller blades, the blades of the propeller being pivoted on an axis at one side of the center.

2. In a device of the character described, an aeroplane, a horizontal propeller for changing the equilibrium thereof, and means for changing the angle of the propeller blades, the blades of the propeller being pivoted on an axis at one side of the center.

3. In a device of the character described, an aeroplane, a propeller located at one side of the machine for changing the equilibrium thereof, and means for changing the angle of the propeller blades, the blades of the propeller being pivoted on an axis at one side of the center.

4. In a device of the character described, an aeroplane, a horizontal propeller located at one side of the machine for changing the equilibrium thereof, and means for changing the angle of the propeller blades; the blades of the propeller being pivoted on an axis at one side of the center.

5. In a device of the character described, an aeroplane, a lifting and depressing pro-

peller for changing the equilibrium thereof, and means for changing the angle of the propeller blades, the blades of the propeller being pivoted on an axis at one side of the

5 center.

6. In a device of the character described, an aeroplane and a propeller for changing the equilibrium thereof on one side of the

aeroplane, the aeroplane being provided with a propeller on one side only. 10

In testimony that I claim the foregoing I have hereunto set my hand.

CARL DIENSTBACH.
